COCKTAIL SHAKER

Helen Hughes Dulany, Chicago, Ill.

Application January 24, 1934, Serial No. 708,156

5 Claims. (Cl. 220—1)

This invention relates to cocktail shakers, drink mixers, and the like, and comprises a novel structure for mixing, agitating and shaking drinks and cocktails.

8 In the present invention, I provide a cocktail shaker having the general exterior shape of a dumbbell, and provided with two opposed interior chambers communicating with each other via the hollow handle of the dumbbell. One of 10 the chambers or compartments is adapted to contain a refrigerating or cooling medium such as cracked ice, ice cubes, etc., while the other compartment is adapted to contain the liquid or combination of liquids to be shaken or mixed. 15 The entire structure possesses numerous advantages, as for example, ease and thoroughness of mixing; capability of being mixed by use of one hand only; non-leakage or spilling of the drink while mixing; slight dilution of the drink with 20 melted ice on account of the segregation of ice and liquid; and other apparent advantages, such as the utilization of the device as a decanter after the ice compartment is disjoined.

In the accompanying drawing, a preferred embodiment is shown, but variations may be made without departing from the spirit and scope of the invention as expressed by the appended claims.

Figure 1 is an elevational view of my dumbbell cocktail shaker, in upright position.

Figure 2 is a view in vertical cross-section of the device shown in Figure 1.

Figure 3 is a view showing the portion of the dumbbell which serves as a decanter when the ice compartment is disconnected therefrom.

Figure 4 is a view in elevation showing the ice compartment as laid aside on the table after the cocktail has been shaken.

Referring to the drawing, the decanter-shaped 40 portion of the dumbbell comprises a unitary structure defined by the oblate spheroidal base 1 welded or otherwise joined to the tubular portion 2 and provided with an angular circular flange member 3 defining a lip. Within the member 3 is a threaded ring 4 seated therein and forming a part or joined to the angular member 3, the extension 5 of which defines an extreme outer lip. The ice compartment 6 is of the general shape corresponding to the liquid compartment 1 and having welded to its opening the threaded ring connection 7, which carries the perforated guard 8 in threaded engagement with said ring 7. A washer or gasket 9 is carried within the channel 10.

55 In the use of the device, the drink mixture

required is poured into the liquid containing chamber of the decanter, and by unscrewing the perforate member 8, ice cubes are placed in the chamber 6. The strainer 8 is then screwed back into position and the entire dumbbell is then 60 assembled by engaging the female thread of the ring 4 with the male thread of the ring 7, the gasket 9 effecting a liquid seal of the joint to prevent leakage. The cocktail can then easily be mixed by grasping the tubular portion 2 with 65 one hand and going through all of the common exercising motions of a person using a dumbbell for exercise. The liquid from the chamber 1 passes through the ice guard 8 and is simultaneously mixed and cooled by contacting the ice 70 in the chamber 6, by its whirling and flowing motion through the tubular handle 2 connecting both chambers. Furthermore, the complete sealing of the device and its convenience in shaking permits a very rapid and effective agitation of 75 the drink. It will be apparent that the device is capable of being shaken in any suitable direction and by any suitable rocking or oscillatory motion, thus giving thorough mixing. The segregation of the ice from the liquid is also highly 80 advantageous in that the drink is not diluted upon standing. As explained hereinabove, the decanter portion which includes the liquid containing base 1 and the tubular handle 2 serves excellently as a liquid container permitting dispensing of the shaken cocktail in intermittent 85 quantities over its pouring lip 5.

If desired, the ice containing base 6 may be charged with sliced fruits and the seeds of which may thus be prevented from passing the guard 8 90 acting as a sieve.

The structure of the present dumbbell device need not be slavishly followed, as minor variations will suggest themselves to those skilled in the art. The screen 8 may be in a plane instead 95 of spherical configuration. It may be in inverted position from that shown. The method of joining the decanter base with the ice chamber may be simplified. A bayonet lock connection may be used where feasible.

100 The general shape of the device being in the form of a dumbbell is preferred since it confers amusement to the shaking operation, but the invention is not restricted to the spherical shape herein shown. The chambers may be made 105 cubical. Obviously, one chamber may be made larger than the other.

A cocktail shaker as herein described may be made of any suitable metal or combination of metals, or of the various non-corrosive metals 110

now on the market. It may be chromium plated or silver lined. If desired, the assembly may be constructed of glass, or partly glass and metal.

What I claim is:

- 5 1. In combination, a decanter element having a tubular portion and a spherical portion, a cooling element having a spherical portion with a throat, a threaded ring in said throat, a perforate element threaded in said threaded ring, and a 10 threaded ring on said decanter element adapted to engage said first named threaded ring.
2. In a cocktail shaker of substantial dumb-bell configuration, a pair of opposed spherical bodies having flat bases and defining ice and 15 liquid containing chambers respectively, a tubular hollow handle member providing a passage for liquid communication from one of said bodies to the other, and an apertured separator removably connected to one of said bodies and lying in the 20 passage between said bodies.
3. In a cocktail shaker of substantial dumb-bell configuration, a pair of opposed spherical bodies defining ice and liquid containing cham-

bers respectively, a tubular hollow handle member providing a passage for liquid communication from one of said bodies to the other, and an apertured separator removably connected to one of said bodies and lying in the passage between said bodies.

80

4. A drink mixer comprising a tubular member having an enlarged member at one end thereof, the said two members constituting a drink containing chamber, and an enlarged member having a constricted opening connected at the other end of the tubular member and detachably related thereto.

85

5. In a cocktail shaker of substantial dumb-bell configuration, a pair of opposed enlarged bodies defining ice and liquid containing chambers respectively, a tubular hollow handle member providing a passage for liquid communication from one of said bodies to the other, and a perforated separator removably connected to one of said bodies and lying in the passage between said bodies.
